The ornamental design for, a fuel tank for an internal-combustion engine, as shown and described.

DESCRIPTION

FIG. 1 is a top, front, and right-side perspective view of a fuel tank for an internal -combustion engine, showing our new design;

FIG. 2 is a top, front, and left-side perspective view thereof; FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view thereof; and,

FIG. 8 is a left side elevation view thereof.

The broken lines showing an internal-combustion engine and a fuel tank cap are for the purposes of illustrating environmental structure and portions of the fuel tank that form no part of the claimed design.
